Primary Examiner — Antoine Duval Davis(74) *Attorney, Agent, or Firm* — Brinks Gilson & Lione(57) **CLAIM**

I claim the ornamental design for a draft chamber, as shown and described.

DESCRIPTION

FIG. 1 is a front perspective view of a draft chamber of the present invention;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines shown in FIGS. 3 and 8 represent unclaimed subject matter and form no part of the claimed design.
